MOLDED PULP TRAY

Philip M. Williams, Oakland, Maine, assignor to Keyes Fibre Company, Portland, Maine, a corporation of Maine

Application March 26, 1958, Serial No. 50,196

Term of patent 14 years

(Cl. D58—13)

Fig. 1 is a top plan view of a molded pulp tray embodying my new design; and

Fig. 2 is a sectional view taken on line 2—2 of Fig. 1.

It is understood that the configurations of the individual elements of the packing member, as shown by the shaded area, are substantially the same throughout the entire packing member.

What is claimed:

The ornamental design for a molded pulp tray, as shown.
